UNITED STATES PATENT OFFICE.

JEROME JAMES LANKFORD, OF GLOBE, ARIZONA TERRITORY, ASSIGNOR TO CLARENCE T. SEIPP, OF GLOBE, ARIZONA TERRITORY.

BOLSTER FOR CONCRETE STRUCTURE.

992,430.

Specification of Letters Patent.

Patented May 16, 1911.

Application filed July 29, 1910. Serial No. 574,512.

To all whom it may concern:

Be it known that I, JEROME J. LANKFORD, a citizen of the United States, residing at Globe, in the county of Gila and Territory 5 of Arizona, have invented a new and useful Improvement in Bolsters for Concrete Structures.

This invention relates to certain new and useful improvements in bolsters to be used 10 in concrete steel construction, especially adapted to be used for supporting the reinforcing rods.

The object of my invention is to provide a device by which the reinforcing rods will 15 be held a proper distance from the forms, and apart so that the rods will at all times be held in their proper positions in respect to the forms.

Another object of my invention is to provide 20 a bolster which is so constructed that the rods will be held in such a manner that all danger of the bolster turning or moving in any way is prevented, the supporting member of the bolster being carried by L-shaped portions which hold the bolster so as 25 to prevent the same from rocking or moving in any way.

A still further object of the invention is to provide a bolster which will strengthen 30 the completed structure when embedded therein to form the reinforcing rod support.

A still further object of the invention is to provide a bolster which is exceedingly simple and cheap in construction, and one 35 which is preferably formed of a bar of galvanized iron so as to prevent the same from rusting when embedded within the structure.

With these various objects in view, my 40 invention consists of the novel features of construction, combination and arrangement of parts hereinafter fully described, pointed out in the claims and shown in the accompanying drawings, in which—

Figure 1 is a horizontal section through a 45 beam showing the application of my improved bolster. Fig. 2 is a section through the same. Fig. 3 is a perspective view of my improved bolster detached.

In the drawing A indicates my improved 50 bolster, which comprises a central inverted U-shaped supporting member, having a central depression forming a seat for the reinforcing rod, said supporting member having L-shaped members extending outwardly 55 therefrom at its ends which support the

same in a vertical position so as to prevent the same from moving in any direction when the reinforcing rod is in position.

The bolster A is preferably formed of a bar of galvanized iron bent centrally to 60 form the inverted U-shaped portion B, which is bent to form a socket or seat C, in which the reinforcing rod is adapted to be placed for holding the same in its proper position. The end portions of the wire extend outwardly at right angles, as shown at D, from the inverted U-shaped portion, and are then bent as shown at E so as to extend parallel with the central U-shaped portion, and may be extended so as to form a similar 70 bolster.

When the bolster is embedded within the mass of concrete, and the reinforcing rods placed in position, the bolster will hold the rods in their proper positions in respect to 75 the forms, and in respect to each other when more than one rod is used, and can be used for supporting the reinforcing rods at any desirable point, and when used in a beam a series of bolsters are placed in the beam to 80 receive the rod in order to prevent the same from moving in any way.

From the foregoing description it will be seen, that I have provided a bolster for supporting the reinforcing rods in concrete 85 structures of all kinds, which will not only hold the rods in their proper positions, but will also be an element of strength to the structure.

What I claim is:

1. A bolster for reinforcing rods comprising a bar bent centrally to form a supporting bar having angled ends and portions extending therefrom at right angles. 90
2. A bolster for a concrete steel structure comprising a bar of non-rusting metal bent centrally to form an inverted U-shaped portion, having a central depression forming a seat to receive the reinforcing rods of the structure; the end portions of said bar being bent outwardly at right angles thereto and then parallel with the inverted U-shaped portion. 95
3. A bolster for supporting reinforcing rods in concrete steel construction comprising a bar bent centrally to form an inverted U-shaped member, having a central depression forming a seat, adapted to receive the reinforcing rod of said structure, the end portions of said bar being bent outwardly 100
- 105
4. A bolster for supporting reinforcing rods in concrete steel construction comprising a bar bent centrally to form an inverted U-shaped member, having a central depression forming a seat, adapted to receive the reinforcing rod of said structure, the end portions of said bar being bent outwardly 110

at right angles thereto and then parallel therewith.

4. As a new article of manufacture, a bolster adapted to be used in concrete steel construction comprising a bar of non-rusting metal bent to form an inverted U-shaped supporting member having a central depression formed therein, adapted to

receive the reinforcing rod of said structure, and the end portions of said bar being bent 10 outwardly in opposite directions from said supporting bars and then parallel therewith.

JEROME JAMES LANKFORD.
